CLAIM

The ornamental design for a capsule, as shown and described.

DESCRIPTION

FIG. 1 is a top perspective view of a capsule showing my new design;

FIG. 2 is a bottom perspective view thereof;

FIG. 3 is a front view thereof, the rear, left and right side views being identical;

FIG. 4 is a top view thereof;

FIG. 5 is a bottom view thereof;

FIG. 6 is another top view thereof, showing the word "TEXT" in broken lines;

FIG. 7 is a top view of a second embodiment thereof, the bottom perspective, front, rear, left and right side and bottom views being identical to those of the first embodiment; and, FIG. 8 is another top view thereof, showing the word "TEXT" in broken lines.

The drawings include relatively thin surface shading lines which represent contour, not surface ornamentation. The diagonal parallel shading lines represent a transparent surface. The horizontal parallel shading lines represent an opaque surface. The broken lines illustrate environment or structure which form no part of the claimed design.
